UNITED STATES PATENT OFFICE.

HENRY D. BOKOP, OF DEFIANCE, OHIO.

RECEPTACLE.

1,190,713.

Specification of Letters Patent. Patented July 11, 1916.

Application filed June 11, 1915. Serial No. 33,596.

To all whom it may concern:

Be it known that I, HENRY D. BOKOP, a citizen of the United States, and a resident of Defiance, in the county of Defiance and 5 State of Ohio, have invented a certain new and useful Receptacle; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 My invention relates to receptacles and particularly to those of the collapsible, compactly folding, liquid carrying type.

The primary object of the invention is the provision of a bucket type of receptacle, 20 which is adapted and particularly intended for use by automobilists in connection with the filling of radiators and gasoline tanks, and when not in use is capable of being folded in compact form for carrying in a tool 25 box, under a seat, or in any other convenient space.

Further objects and advantages of the invention will be apparent from the following detailed description thereof.

30 The invention is fully described in the following specification, and while, in its broader aspect, it is capable of embodiment in numerous forms, a preferred embodiment thereof is illustrated in the accompanying 35 drawings, in which,—

Figure 1 is a perspective view of an article embodying my invention with a part broken away. Fig. 2 is a sectional detail of the rim portion thereof, and Fig. 3 is a perspective 40 view of the straining sieve removed from the receptacle.

Referring to the drawings, 1 designates a body of a receptacle embodying the invention, which body is in bucket form and composed of canvas, rubber, water proof fabric or other suitable material of a pliant nature. The top or upper end of the body 1 is open and provided with a frame or reinforcing ring 2 from which the pliant body material 50 is suspended.

3 designates a bail which is pivoted to the ring 2 centrally and at opposite sides thereof and is of suitable size and shape to adapt it to be turned down within the ring in the 55 plane thereof.

The body 2 has its bottom provided, preferably adjacent to one edge thereof, with a downwardly projecting spout 4, which opens into the interior of the bucket and serves as a discharge spout for the contents of the 60 bucket. This spout is of flexible hose form, and is preferably of such a length that its free end may be raised to near the top of the bucket, so that when raised, as indicated by the dotted line position in Fig. 1, liquid will 65 not be discharged therethrough from the interior of the bucket. A hook 5 is attached to the spout 4 at or near the free end thereof and is adapted to be engaged over the ring 2 or top 1 of the bucket to retain the spout 70 in the upturned dotted line position shown.

The spout 4 which is preferably but not necessarily composed of the same material as the body part 1 of the bucket or receptacle, has its inner end enlarged in outward tapering or gradually diminishing form, as shown at 4^a, to provide a holding chamber for a cup-form of sieve 6, which is removably inserted into the spout enlargement from within the receptacle and serves to strain 80 water, gasoline or other liquid as it is discharged from the receptacle. The spout 4 may be provided with a valve member 7 of clamp or other suitable form, which is operable to close the spout when desired. 85

It is evident that my improved receptacle is most admirably adapted for use by automobilists, as the provision of the flexible spout 4 very materially facilitates a filling of radiators, gasoline tanks and the like 90 without the use of a funnel. The flexible feature of the spout combined with the length thereof also enables it to serve in the capacity of a valve in that a raising of the discharge end of the spout to a point above 95 the level of liquid within the receptacle will prevent a discharge of the liquid contents of the receptacle. The collapsible nature of the receptacle body and spout enables the article to be folded in flat compact form 100 within practically the confines of the ring 2 so that the article can be packed in a space which is no larger than is necessary for the receiving of the ring 2.

I wish it understood that my invention is 105 not limited to any specific construction, arrangement, or form of the parts or material, except in so far as such limitations are specified in the claim.

Having thus described my invention, what 110

I claim as new, and desire to secure by Letters Patent, is,—

A bucket of the class described comprising a top ring, a bail pivotally attached to said ring and capable of being folded in flat relation to said ring in the plane thereof, a collapsible body part depending from said ring and having a flexible spout extending from the bottom thereof, said spout being

10 of considerable length and having its inner

end provided with an enlargement which reduces in size outwardly from said body part, a sieve member removably disposed within said spout enlargement, and a hook carried by the spout for engagement over the upper 15 edge of the bucket to hold the free end of the spout in elevated relation to the bucket.

In testimony whereof, I have hereunto signed my name to this specification.

HENRY D. BOKOP.
